UNITED STATES PATENT OFFICE.

CHARLES W. HALL, OF KEYSTONE, WEST VIRGINIA.

SHAKER-GRAVE.

1,307,777.

Specification of Letters Patent. Patented June 24, 1919.

Application filed March 14, 1918. Serial No. 222,397.

To all whom it may concern:

Be it known that I, CHARLES W. HALL, citizen of the United States, residing at Keystone, in the county of McDowell and 5 State of West Virginia, have invented certain new and useful Improvements in Shaker-Grates, of which the following is a specification.

This invention relates to furnace grates 10 and more particularly to improvements in grates of the shaker type.

It is the primary aim of the present invention to provide in a furnace grate of the type mentioned, a novel construction of the 15 dead plate designed to prolong the life of the grate and to be so constructed and arranged as to be prevented from sagging or being otherwise rendered incapable of properly supporting the bearing bars of the 20 grate. Ordinarily the dead plates of furnace grates of the type mentioned are so located as to be exposed to the intense heat in the fire box and as a result the dead plates soon sag or become otherwise distorted, 25 thereby impairing the efficiency of the grate as a whole. In an effort to overcome this disadvantage it has been proposed to provide supports for these plates extending downwardly into the the ash pit and to the 30 floor of the said pit, but these supports interfere with cleaning of the ash pit and are otherwise undesirable. Therefore, the present invention has as its object to provide a dead plate so constructed as to support the 35 bearing bars of the grate in a substantial manner and against any lateral play whatsoever, the said dead plate being furthermore so located and mounted within the fire box as not to be subjected to the direct heat 40 from the burning fuel.

The invention also has as a further object to provide a novel construction and arrangement of the bearing bars for the grate sections.

45 In the accompanying drawings:

Figure 1 is a perspective view of the shaker grate embodying the present invention removed from the furnace;

Fig. 2 is a vertical longitudinal sectional 50 view through the grate;

Fig. 3 is a vertical transverse sectional view through the grate;

Fig. 4 is a perspective view looking at the under side of the dead plate of the grate.

55 In the drawings, while the grate is illustrated as removed from the furnace, in a

sense, nevertheless there is illustrated a portion of the front of the furnace indicated in general by the numeral 1, the said front having the usual door openings 2 leading to 60 the ash pit and the door opening 3 communicating with the fire box. The dead plate of the grate is indicated in general by the numeral 4 and the said plate is preferably in the nature of an integral casting of 65 a length to extend the entire width of the rear side of the front 1 of the furnace. The upper and under faces of the dead plate are located in parallel planes and are flat, and upon its under side adjacent each end 70 the dead plate is formed with a reinforcing boss 5 which extends inwardly from the forward edge of the plate and terminates about midway between the forward and rear edges of the said plate. A similar reinforcing 75 boss 6 is formed upon the under side of the plate midway between the bosses 5 and the plate is formed in its upper side with seats 7 and 8 located respectively above the reinforcing bosses 5 and 6. The seats 7 and 80 8 open through the forward edge of the plate and through the upper face thereof and are designed to receive the forward ends of the bearing bars of the grate, as will be presently described. The seats 7 and 8, in 85 shape, are preferably rectangular and it will be understood that by the provision of the bosses 5 and 6 the dead plate 4 is suitably reinforced at the points of location of the said seats. By reference to Fig. 2 of the 90 drawings it will be observed that the dead plate is to be positioned with its rear edge abutting against the face of the furnace front 1, and in order to provide for attachment of the plate to the said furnace front 95 100 and to brace the plate in its attached position, the under side of the plate is formed at suitable intervals with depending lugs 10 and 11. By reference to Fig. 4 it will be noted that one of the lugs 10 is located at 100 each end of the plate rearwardly of the respective boss 5 and one midway between the ends of the plate and rearwardly of the boss 6, the lugs 11 being located between the lugs 10 and all of the lugs being designed to rest 105 or seat firmly against the inner face of the furnace front 1 in the manner shown in Fig. 2. Bolts 12 are secured through the furnace front and through the openings in the lugs 10 and serve to secure the dead plate 110 in position. In order to further reinforce the dead plate 4, it is formed upon its under

side with an integral downwardly extending flange 5^a which extends longitudinally of the said plate near the forward edge thereof and between the bosses 5 and 6. The numeral 5 13 indicates a bridge wall within the furnace, and the rear ends of the bearing bars are built into this wall and supported thereby.

In supporting the grate sections there are 10 provided two side and one intermediate bearing bars indicated, respectively, by the numerals 17 and 18. Each of the bearing bars is substantially of truss formation to provide against sagging and the bars are formed 15 at their ends with extensions 19 and 20, respectively, which extensions are rectangular in form. By reference to Fig. 3 it will be observed that the bearing bar 18 has the form of the two side bearing bars 17 placed 20 face to face, and in fact in casting the bearing bar 18 I dispose side by side the two patterns in the use of which the side bars 17 are cast and thus not only save the expense of a separate pattern, but also properly 25 increase the dimensions of the intermediate bar as the same is required to support the adjacent ends of both sets of grate sections. In other words, while the bar 18 is of the same general contour as the bars 30 17, it is of a double thickness as also are its projecting ends 20. Referring now to Fig. 1 of the drawings it will be observed that the projecting ends 19 and 20 at the rear of the bearing bars are built into the 35 bridge wall 13 as previously stated. Also by reference to the said figure it will be observed that the projections 19 and 20 at the forward ends of the bearing bars are seated, respectively, in the seats 7 and 8 in 40 the dead plate and in such a manner that the upper sides of the bars will be flush with the upper face of the said plate and the bars at their forward ends will be held against relative lateral displacement. 45 At suitable intervals the bearing bars 17 and 18 are formed in their upper sides with trunnion bearings or recesses 23 to receive trunnions 24 at the ends of the 50 grate sections, the sections extending transversely between the intermediate bearing bar 18 and the two side bars 17. The trunnions 24 at the outer or relatively remote ends of the sections rest in the bearings 23 in the bearing bars 17, whereas the trunnions 55 at the inner or adjacent ends of the grate sections rest in the bearings in the bearing bar 18, these latter bearings being, of course, substantially twice the length of the bearings in the bars 17 so that each receives the 60 trunnions of corresponding grate sections of the two sets. Inasmuch as the grate sections in themselves may be of any of the ordinary forms, it is not thought necessary to specifically describe the same, it being 65 sufficient to note that the said sections, which

are indicated in general by the numeral 25, are suitably reticulated to provide for draft. To provide for shaking of the grate sections, arms 26 extend beneath the sections of each set and all of the arms of the sections of each set are connected by one or a pair of longitudinal bars 27 pivoted to the lower ends of the arms 26 and connected by a link 28 with a suitable shaking lever 29 mounted upon the furnace front.

From the foregoing description of the invention it will be understood that there is provided, in a grate of the type mentioned, a dead plate which extends the entire width of the furnace front, which is so mounted in place as to obviate the employment of supportings extending downwardly into the ash pit, which is so located as to lie forwardly of the bed of burning fuel upon the grate, and is, consequently, not subjected to the direct heat from the fuel, and, which supports the forward ends of the bearing bars for the grate sections in a substantial manner and effectually prevents rattling of the bars and the lateral displacement of their 90 said forward ends.

Having thus described the invention, what is claimed as new is:

1. In a furnace, the combination with a front, of a dead plate secured to the inner side of the furnace front and provided in its upper face at its forward edge with spaced seats opening therethrough, transverse bosses arranged beneath the seats, bearing bars having reduced portions fitting within the seats and provided with vertical shoulders bearing against the adjacent bosses, and grate sections journaled in said bearing bars.

2. In a furnace, the combination with a front, of a dead plate having one longitudinal edge thereof provided with depending perforated lugs bearing against the inner side of said front and provided in its upper face at its forward edge with spaced seats opening through said edge and immediately below the seats with transverse bosses, bearing bars having reduced portions fitting in said seats and provided with vertical shoulders bearing against the adjacent bosses, grate sections journaled in the bearing bars, and fastening devices extending through the furnace front and through the perforations in the lugs for securing the dead plate in position on the furnace front.

3. In a furnace, the combination with a front, of a dead plate having a flat upper surface and provided at its rear longitudinal edge with depending perforated lugs and at its forward longitudinal edge with spaced seats terminating short of the lugs, said plate being provided on its lower face and beneath the seats with transverse bosses connected by a longitudinal rib, bearing bars having reduced portions fitting within the

seats and provided with vertical shoulders bearing against the adjacent faces of the bosses, grate sections journaled in the bearing bars, and fastening devices extending 5 through the front of the furnace and through the perforations in the lugs for securing the dead plate in position on the furnace front.

4. In a furnace, the combination with a 10 front, of a dead plate bearing against the inner side of the furnace front and provided at one longitudinal edge thereof with spaced depending perforated lugs and at its other longitudinal edge with terminal and intermediate seats opening through said longitudinal edge and the top of the plate, the intermediate seat being approximately twice the width of the terminal seats, transverse 15 bosses arranged on the lower face of the plate 20 and connected by a longitudinal rib, said bosses having their forward edges disposed flush with the forward edge of the dead plate, bearing bars having reduced portions fitting in said seats and provided with vertical shoulders bearing against the adjacent 25 faces of the transverse bosses, grate sections journaled in the bearing bars, and fastening

devices extending through the furnace front and through the perforations in the depending lugs for securing the dead plate in position on said furnace front. 30

5. As an article of manufacture, a dead plate for furnace grates comprising an elongated body portion having a flat upper surface and provided with terminal and intermediate seats opening through one longitudinal edge of the plate and terminating short of the other longitudinal edge thereof, the intermediate seat being approximately 35 twice the width of the terminal seats, there being transverse reinforcing bosses arranged beneath the seats and of the same length thereof with their outer faces disposed flush with the adjacent longitudinal edge of the plate, longitudinal ribs connecting the transverse bosses and spaced inwardly from the forward longitudinal edge of the plate and lugs depending from the bottom of the plate at the rear longitudinal edge thereof, certain 40 of said lugs being provided with transverse 45 openings for the reception of fastening devices. 50

In testimony whereof I affix my signature.
CHARLES W. HALL. [L. s.]
